UNITED STATES PATENT OFFICE.

WILLIAM S. FERRIS, OF ELKHART, INDIANA.

CHAIR.

Application filed January 25, 1924. Serial No. 688,415.

My invention relates generally to improvements in chairs, but relates more particularly to improvements in so called tablet arm chairs.

5 The general object of my invention is to provide a tablet arm chair which shall be of such construction that it can be adjusted to meet the individual requirements of the user and still maintain the proper relation 10 of the parts for most comfortable use.

I aim also to provide a tablet arm chair construction of simple, strong and durable form and in which the back rest and tablet arm shall both be adjustable in order better 15 to fit the individual characteristics of the user.

My invention consists generally in a tablet arm chair of the form, arrangement, construction and the co-operation of the parts 20 thereof, whereby the above named objects, together with others that will appear hereinafter, are attainable, and my invention will be more readily understood by reference to the accompanying drawings which 25 illustrate what I consider at the present time to be the preferred embodiment thereof.

In said drawings:

Fig. 1 is a side elevation of a chair embodying my invention;

30 Fig. 2 is a detail fragmentary front view taken substantially along the line 2—2 of Fig. 1;

Fig. 3 is a detail sectional view upon an enlarged scale taken substantially along the 35 line 3—3 of Fig. 1; and

Fig. 4 is a detail sectional view, on an enlarged scale, substantially along the line 4—4 of Fig. 3;

The exemplary chair here shown comprises the metal legs 1 which are suitably connected by braces 2. The chair seat 3 in this instance, is carried upon a chair frame composed of front and rear strap members 4 and 5 and the side strap members 6 and 7. 40 The chair is provided with a back rest 8 which in turn is swingably carried in arms 9 which upstand from the metal seat frame and are secured thereto by means of bolts 10. The arms 9 are suitably braced by means of 45 the curved braces 11 which are secured to the seat frame by means of bolts 12 and to the arms 9 by means of the loose rivets 13. The arms 9 and the seat frame side members 6 and 7 are provided respectively with 50 a plurality of holes 14 and 15 so that the

angular position of the back may be adjusted, one such adjusted position being shown in Fig. 1 by means of dotted lines.

A tablet arm or table-like member 16 is supported in a novel manner. Thus at its 60 rear end it is supported by a strap metal member 17 which is secured to the bottom of the tablet arm as by means of screws or other fastening devices 18, and the end portion 19 is twisted at an angle so that it presents a flat face to the arm 9 to which it is loosely riveted or otherwise secured to permit of the necessary swinging movement, as indicated at 20.

At the forward end or part the tablet arm 70 is supported by a standard 21 which is suitably secured to the seat supporting frame as indicated at 22 and 23. The standard 21 in this instance is in the form of a metal tube which terminates in close proximity to the 75 under surface of the tablet arm. Over the top of the tube I secure a U-shaped metal clip or member 24 which is secured firmly in place as by means of rivets 25. The edges 26 and 27 of the clip 24 form good bearings 80 for the face portions of the angle members 28 and 29 with respect to which they are relatively movable. The angle members 28 and 29 are firmly secured to the under face of the tablet arm, as by fastening devices 30. 85 The depending spaced portions of the members 28 and 29 are provided with a plurality of aligned holes 31 and a bolt 32 passes through a pair thereof and through an opening 33 provided in the standard 21 and 90 the encompassing U-slip 24. By this means the tablet arm is very rigidly attached to the front support and yet it is so arranged that proper adjustment can be made to accommodate the movement which takes place 95 as the back rest is adjusted rearward or forward, to the individual requirements of the user. The flat surfaces of the edge portions of the U-clip cooperate with the angle members 28 and 29 in providing a construction 100 which firmly resists the racking action to which the tablet arm is peculiarly subjected in use.

The many advantages of my chair will now be understood by those skilled in the 105 art to which this appertains without further comment.

I claim:

1. A chair embodying therein a frame, a back rest supporting frame secured to the 110

first mentioned frame, said securing means being formed to permit vertical adjustment and forward and rearward swinging movement, a tablet arm, means connected to the 5 back rest supporting frame for supporting the rear part of the tablet arm, a support for the forward part of the tablet arm, and means adjustably connecting the tablet arm to the last mentioned support whereby relative forward or rearward adjustment may be had.

2. A chair embodying therein a seat supporting frame, a back rest supporting frame adjustably secured thereto, an angularly 15 disposed brace extending between an upper portion of the back rest supporting frame and the seat supporting frame, a tablet arm, means connected to the back rest supporting frame for supporting the rear part of 20 the tablet arm, a support for the forward part of the tablet arm, and means adjustably connecting the tablet arm to the last mentioned support whereby relative forward or rearward adjustment may be had.

25 3. A chair embodying therein a frame, a seat thereon, a back rest member mounted on said frame for both a vertical adjustment and a forward and rearward movement, a standard on said frame, a tablet arm positioned above the seat, means connecting said tablet arm to said back rest member, a plate secured to the tablet arm and having a face portion extending in a lengthwise direction thereof, said plate having a plurality 30 of openings therein, and a bolt associated with one of said openings and engaging said standard.

4. A chair embodying therein a frame, a seat thereon, a back rest member mounted 35 on said frame for both a vertical adjust-

ment and a forward and rearward movement, a standard on said frame, a tablet arm positioned above the seat, means connecting said tablet arm to said back rest member, an angle plate having a face portion secured 45 to the under part of said tablet arm and a face portion extending in a lengthwise direction thereof together with means for securing the latter face portion and standard together in adjusted position. 50

5. A chair embodying therein a frame, a seat thereon, a back rest member mounted on said frame for both a vertical adjustment and a forward and rearward movement, a standard on said frame, a tablet arm positioned above the seat, means connecting said tablet arm to said back rest member, means secured to the upper end of said standard and presenting bearing faces, a pair of plates secured to the tablet arm and spaced apart 60 thereon such distance that they engage said bearing faces together with means for securing said plates to the standard in adjusted position. 65

6. A chair embodying a seat frame, a back member, means operatively connecting said back member to said seat frame so that said back member may be adjusted vertically and then locked in said adjusted position, a brace connecting said back member and said 70 seat member, an upright support connected to the forward part of a seat frame, and a tablet arm having a pivotal connection at its rear end with said back member and having a longitudinal adjustable connection at 75 its other end with said support.

In testimony whereof, I have hereunto set my hand, this 18 day of Jan., 1924.

WILLIAM S. FERRIS.
